GAME

Henry J. Stitt, New York, N. Y., assignor to H. F. Eldridge Inc., New York, N. Y.

Application March 7, 1936, Serial No. 67,572

8 Claims. (Cl. 88—26)

This invention relates to a game, and particularly to what may be termed a game of amusement adapted to be thrown on a screen for the amusement of an audience.

5 Another object of the invention is to provide an improved game structure which may be placed in a projecting machine so that a portion thereof may be projected on a screen and coat with cards carried by an audience looking at the screen 10 or at least that part of the audience which co-operate in playing the game.

A further object, more specifically, is to provide a game having a slide for projecting machines wherein a rotating indicating member is 15 presented and actuated by intermittent blows or impulses from an air driven member.

In the accompanying drawing:

Fig. 1 is a side elevation of a device embodying the invention;

20 Fig. 2 is a view similar to the slide shown in Fig. 1 but on an enlarged scale and with certain parts broken away;

Fig. 3 is a sectional view through Fig. 2 approximately on the line 3—3;

25 Fig. 4 is an elevation of a modified form of wheel to that shown in Figs. 1 and 2;

Fig. 5 is a sectional view through Fig. 4 on the line 5—5;

30 Fig. 6 is an elevation of a card coating with the numbers and pointer illustrated in Figs. 1 and 2.

Referring to the accompanying drawing by numerals, 1 indicates a filler which may be a piece of wood, fiber, bakelite or other material, 35 and which spaces the members 2 and 3 which may be glass, cellophane, celluloid, or other transparent material. A covering or an enclosure 4 holds the parts 1, 2 and 3 together, said enclosure being paper, leather, metal or other material, 40 which snugly fit as shown in Fig. 3 and which may be held in place by adhesive, if desired.

The filler or spacer 1 is provided with a large cutout 5 as shown in Fig. 2 and a small cutout 6 which merges at 7 into cutout 5. An air entrance passageway 8 is formed in the spacing member 1 and also an air vent passageway 9 is formed in the same spacing member, passageway 9 being preferably of greater diameter than passageway 8 so as to allow the air to escape 50 easily. A connecting pipe 10 is screwed into the spacer or filler member 1 as shown in Fig. 2 so as to register with the passageway 8. A rubber hose 11 is disengageably secured to the member 10 and also to a collapsible bulb 12.

55 When the device is used bulb 12 is collapsed

in more or less quick succession so as to direct air through hose 11 and pipe 8 into the cutout 6 and against the teeth 13 of the motor or impelling wheel 14. The bulb 12 is provided with an air inlet valve (not shown) whereby air may be drawn in through the valve when the bulb expands and is prevented from passing through the valve when the bulb is deflated but the air moves from the bulb when being deflated through tube 11 as described.

10 The motor or impelling wheel 14 is carried by a pin 15 which is journalled in the members 2 and 3 so that the wheel 14 may freely rotate. An impelling bumper or friction member 16 is provided and has end sections 17 and 18 fitted into 15 suitable slots so that the central part of this member will project beyond the various teeth 13 and consequently strike the corrugated or roughened surface 19 of the ring 20. By this arrangement the impelling bumper 16 will strike and 20 move ring 20 upon each rotation of wheel 14. This gives successive impulses or blows to the ring 20 so that the same may rotate at a high rate 25 of speed and gather an appreciable momentum. When the person operating the device ceases to 25 actuate the bulb 12, wheel 14 will stop but the ring 20 will continue to move under the action of inertia but will eventually stop.

Ring 20 is provided with a cross bar 21 which may be integral with the ring or may be merely 30 rigidly secured thereto. A pointer 22 extends from bar 21 and may be integral therewith and made independent and secured thereto. Ring 20, bar 21 and arrow or pointer 22 may be made from 35 fiber, celluloid, metal, wood, bakelite or other material, which has some desired weight so that a desired momentum may be produced therein. A pivotal support 23 extends through bar 21 and into or through the respective members 2 and 3 so that the ring 20 is freely and rotatably 40 supported.

On one of the transparent members, preferably member 3, there is provided a scale 24 and an enclosed space 25 having legends 26 which are shown as numbers. The numbers are from 45 zero up to 95 although the graduations indicate from zero up to 99. The parts are made of a proper proportion to permit the part 27 to act as a lantern slide and be slid into the proper support in a projecting machine. When the slide is first 50 inserted into the projecting machine and the light is turned on, the graduation 24, legend 26, bar 21 and pointer 22 will be thrown on to the screen. The inner portion of ring 22 will also 55 be thrown on to the screen although the cutaway

part 28 may be of a size to coincide with the inner surface of ring 20 and thereby completely obscure this ring.

After the light has been turned on the operator 5 actuates the collapsible bulb 12 and the pointer 22 and associated parts will begin to rotate. After a desired momentum has been secured the operator ceases to actuate bulb 12, but the ring 20 and parts carried thereby will continue to 10 rotate under the action of momentum for a short time. The pointer 22 will naturally come to rest, pointing at some number, namely one of the legends 26 or some graduation between two legends.

15 When used in the manner just described, there is a card, namely card 29, provided for each person in the theater or place where the projector is used. Various rules of the game may be used, and as an example one rule may require that any- 20 one holding card 29, in order to win a prize, must be the first to check off one of the horizontal rows of numbers. If the pointer 22 stops at 9 the first time the device is actuated, the holder of card 29 will check off the numeral 9. 25 If the second actuation of the device causes pointer 22 to stop at 15, the holder of card 29 may check off the numeral 15. As the device is moved from time to time, the holder of card 29 will check off any number on his card pro- 30 vided the pointer 22 stops at that number. If he can check off one horizontal row of numbers before anyone else, he will secure the first prize. The other parties in the theater or other place of amusement will be also checking off their cards, 35 and preferably the rules arrange the cards so that no two cards will be identical as far as numbers are concerned. The device may be operated until the pointer 22 has stopped at all the numbers, or the device may be operated for a given 40 time, as for instance ten or fifteen minutes.

In Figs. 4 and 5 a slightly modified form of ring is shown, namely ring 20'. In this form of ring the parts are made of glass, celluloid, or other transparent material, and a pointer 22' is 45 applied to the cross bar 21'. The pointer 22' may be opaque paint or may be made of metal or other material and secured in place by adhesive or in any other desired way. When the wheel 20' is used, all the parts being transparent, nothing will 50 be seen on the screen except the pivotal pin 28' and the pointer 22'. This will be somewhat mystifying but the pointer 22' will function in a similar manner to the pointer 22.

I claim:

55 1. A slide apparatus comprising a casing having transparent side members, a wheel freely rotatable between said side members, an annular scale arranged on one of the side members and concentric with said wheel, said wheel being pro- 60 vided with a cross bar, means extending through said cross bar for rotatably mounting said wheel, a pointer carried by said cross bar, said pointer being positioned so that the end thereof will pass over said graduations, an impeller adapted to 65 rotate said wheel, said impeller being provided with a number of tangentially arranged teeth and a projecting bumper extending outwardly far enough to strike said wheel upon each rotation of the impeller to cause the wheel to rotate, and 70 means for directing air against said wheel to cause said impeller to rotate.

2. A slide apparatus adapted to be used in a projecting machine, comprising a rotatable ring-like wheel having a pointer carried thereby, an 75 impeller independently of the ring-like wheel but

formed with a protuberance adapted to strike the ring-like wheel upon each rotation of the impeller so as to cause the ring-like wheel to rotate, and means for directing air against said impeller to cause the same to rotate.

3. A game apparatus adapted to be used with a projector, including means for intermittently providing a supply of air under pressure and a slide connected with said means, said slide being adapted to be inserted into the projector, 10 said slide having an inlet and outlet passageway for said air, an impeller rotatably arranged in the slide and projecting into the path of said air, said impeller having a protruding member, a rotatably mounted ring member provided with 15 an arrow and positioned to be engaged by said protruding member upon each rotation of the impeller so as to be rotated thereby, a pair of glass panels supporting and confining said im- 20 peller and said ring-like member, and means on one of said panels presenting an annular scale positioned concentric with said ring member whereby the ring member carrying the arrow after being impelled by the impeller will come to rest position with the arrow pointing to some 25 mark on the annular scale.

4. A slide of the character described comprising a pair of transparent supporting plates, a cover for said supporting plates, said cover having a cutout on each side, a spacer having a pair of cutouts merging at one point, an air passageway leading into one of said cutouts and an air passageway leading from the last mentioned cutout, a ring member rotatably mounted between said plates opposite the cutouts in the casing and in one of the cutouts in the spacer, said ring member being provided with an arrow, means on one of said plates presenting an annular scale concentric with said ring member, and an air actuated impeller arranged between 30 said plates and positioned in the other of the cutouts of the spacer, said impeller being provided at one point on its periphery with a projection adapted to strike the periphery of said ring member to intermittently impel the ring member so as to cause the same to rotate whereby the ring member carrying the arrow after being impelled by said impeller will come to rest position with the arrow pointing to some mark on the annular scale.

5. A slide apparatus of the character described, provided with a pair of transparent spaced plates, a spacer having a pair of cutouts merging at one point, an air passageway leading into one of said cutouts and an air passageway leading 55 from the last mentioned cutout, a transparent ring member positioned in one of said cutouts between said plates and pivotally mounted on said plates, said ring member being provided with an opaque arrow, means on one of said transparent plates presenting an annular scale concentric with said ring member, and an air actuated impeller pivotally mounted between said plates in the other of said cutouts, said im- 60 peller being formed with protruding means for intermittently engaging said ring member to intermittently give the ring member a rotary im- 65 pulse whereby the ring member carrying the arrow after being driven by said impeller will come to rest position with the arrow pointing to some 70 mark on said annular scale.

6. A game apparatus of the character described, including an annular scale, a pointer adapted to move over said scale, a rotatable member concentric with said scale carrying said 75

pointer, a rotatable impeller formed with a protuberance adapted to engage said ring member upon each rotation for giving the ring member a rotary impulse, means for directing air against said impeller for causing the same to rotate, and means forming a passageway for the exhaust of said air whereby the rotatable member carrying said pointer after being driven by said impeller will come to rest position with the pointer pointing to some mark on said annular scale.

7. A slide structure comprising a spacer having a pair of cutouts merging at one point, an air passage leading into one of said cutouts and an air passage leading from the last mentioned cutout, an impelling wheel rotatably mounted in the last mentioned cut out, a ring rotatably mounted in the other cut out and positioned to be actuated by said impelling wheel, a transparent member on each side of said spacer, a pointer carried by said ring, and an annular scale on one of said transparent members concentric to the rotatable ring whereby the rotatable ring carrying said pointer after being driven by the impelling wheel will come to a rest position pointing to some mark on said annular scale.

8. A slide structure including a spacer having

a pair of cutouts merging at one point, an air passage leading into one of said cutouts and a second air passage leading from the last mentioned cutout, said second air passage being spaced from the first mentioned air passage, an impelling wheel having a protuberance at one point rotatably mounted in the last mentioned cutout, a ring rotatably mounted in the other cutout and positioned to be actuated by said protuberance on said impelling wheel upon each rotation of the impelling wheel, a transparent member on each side of said spacer, said transparent members being provided with aligned apertures substantially aligned with the center of the cutout in which said ring is mounted, a journal member positioned in said apertures extending through the center of said ring for rotatably supporting the ring, a pointer carried by said ring, and an annular scale on one of said transparent members concentric with the rotatable ring whereby the rotatable ring carrying said pointer after being driven by the impelling wheel will come to a rest position pointing to some mark on said annular scale.
